INVENTOR
James H. Williams,

ATTORNEY

UNITED STATES PATENT OFFICE.

JAMES H. WILLIAMS, OF LEVERETT, MASSACHUSETTS.

WRENCH.

1,337,678.

Specification of Letters Patent. Patented Apr. 20, 1920.

Application filed May 1, 1917. Serial No. 165,779.

To all whom it may concern:

Be it known that I, JAMES H. WILLIAMS, a citizen of the United States, residing at Leverett, in the county of Franklin and 5 State of Massachusetts, have invented certain new and useful Improvements in Wrenches, of which the following is a specification.

This invention relates to certain new and 10 useful improvements in wrenches.

The primary object of the invention is to provide a wrench which may be quickly adjusted to fit the nut to which it is to be applied.

15 Another object of the invention is to provide a wrench so constructed that the force exerted on the handle in turning the nut will be communicated to the jaw members in such a manner that the pressure of the 20 latter upon the nut will be increased in proportion to the resistance offered by the nut.

25 A further object of the invention is to provide a wrench having an outer jaw of peculiar construction which is adapted to grip the smallest size nut.

The above and other objects will be more readily understood from the following description and drawings in which drawings:—

Figure 1 is a side elevational view of my improved wrench.

Fig. 2 is an edge view and

35 Fig. 3 is a view similar to Fig. 2, looking in the opposite direction.

In the drawings wherein is illustrated the preferred form of my invention the numeral 1 indicates a handle which is rounded in cross section and has one end ex- 40 tended to provide the flattened and down- wardly curved shank 2, the latter being equipped on its upper surface with the curved jaw face 3. The outer jaw, as in- 45 dicated at 4 is also curved and is equipped with a forked shank 5 which embraces the inner jaw 2 at a point adjacent the han- 50 dle 1 and is adapted to be pivotally secured thereto by any suitable means such as the pivot bolt 6. The outer jaw 4 is provided with a plurality of jaw faces as indicated at 7 and 8 respectively, the face 7 being formed

on the inner edge of the free end of said jaw and the face 8 being formed on the lower edge of the shank 5. The jaw 4 is further provided with a nut engaging shoulder 9 arranged between the jaw faces 7 and 8 and adapted for coöperation therewith. Coöperation between the shoulder 9 and the jaw faces 7 and 8, as will be hereinaf- 55 ter explained, is attained by forming the 60 said shoulder with straight sides 10 and 11, the side 10 thereof being arranged to extend at right angle to the jaw face 7 and the side 11 being similarly arranged with respect to the jaw face 8. 65

In the ordinary use of my improved wrench, the nut to be removed or applied, is clamped between the jaw face 7 and the inner jaw 2, in this instance the side 10 of the shoulder 9 coöperates with the face 7 to 70 hold the nut stationary between the jaws 2 and 4. When, however, the wrench is to be applied to a nut which is too small to be conveniently clamped between the face 7 and the jaw 2, the nut is adapted to be re- 75 ceived between the side 11 of the shoulder 9 and the jaw 2. In this manner it will be seen that even the smaller sized nut can be firmly clamped against the face 8 of the shank 5, the adjacent side of the shoulder 80 9 and the inner jaw face 3.

Having thus fully described my invention, I wish it to be understood that I do not limit myself to the preferred form shown but may make such changes in construc- 85 tion and arrangement of the parts as may come within the scope of the invention.

What I claim is:—

A wrench comprising a shank provided with a smooth cam head jaw, a loosely 90 swinging complementary jaw pivotally mounted thereon provided with a plurality of steps providing angular recesses adapt- 95 ed to receive and embrace the corner of the nut to seat varying sized nuts.

In testimony whereof I affix my signature in presence of two witnesses.

JAMES H. WILLIAMS.
